UNITED STATES PATENT OFFICE

PAUL COMBS, OF SOUTH BOSTON, VIRGINIA

FIREPLACE PROTECTOR

Application filed April 25, 1929. Serial No. 358,060.

This invention relates to a means adapted to protect the brick work or masonry about a fireplace, particularly the corners, to avoid breaking and cracking thereof.

5 It is aimed to provide the device of such construction that it may be made in a single piece and so that it may be anchored in place by the side members and by laterally extending elements adapted for keying into cement 10 used in the masonry work.

The more specific objects and advantages will become apparent from a consideration of the description following taken in connection with accompanying drawings illustrating the invention and in which:

Figure 1 is a front elevation of the device,
Figure 2 is a top plan view thereof,

Figure 3 is a sectional view taken on the line 3—3 of Figure 1, and

20 Figure 4 is a cross sectional view taken on the line 4—4 of Figure 1.

Referring specifically to the drawing, the protector is generally shown at 10 and is in the form of an arch and is made in a single piece of metal, preferably being a casting. This protector or arch 10 has side members 11 and a top member 12. The side members 11 are of angle form in cross section as shown particularly in Figure 3 so as to engage and cover and protect the upright corner of the masonry 13, at a fireplace 14. Likewise, the cross member 12 is of angle form in cross section so as to receive, intimately engage and protect an adjacent corner 15 of the masonry of the fireplace 14.

The lower edges of the side members 11 are preferably sunk several inches into cement or concrete 16 at the base.

The horizontal angle 17 of the cross member 12, is extended beyond the side members 11 and in the rear thereof to form key projections 18. These projections extend into the brick work or masonry 13 and 15, in the course of erection of the fireplace and they have openings 19 therein adapted to form key ways for mortar used in the construction of the brick work or masonry and which mortar serves as keys when set, thus aiding the lower ends of the portions 11 in holding 50 the protector in place.

A forwardly extending flange or rib 20 is provided on the side members 11 and cross member 12, constituting a reenforcement for the parts and being capable of giving the protector an ornamental or artistic appearance. In addition, the flange 20 at the side members 11 may have projections or hooks 21 upon which shovels, fire tongs, or other accessories for a fireplace may be hung or suspended.

Various changes may be resorted to provided they fall within the spirit and scope of the invention.

I claim as my invention:

1. A protector of the class described comprising a frame of arch shape made in a single piece and an integral reenforcing rib extending forwardly from the protector, and an accessory-supporting element extending integrally from the protector.

2. A protector of the class described comprising a frame of arch shape made in a single piece and substantially of angle construction throughout, one of the angles being extended to form a key member adapted for disposition in masonry to secure the protector in place.

3. A protector of the class described made in a single piece and of arch form, the lower ends of the sides being adapted for anchoring, said protector being of angle form throughout, one of the angles being extended laterally beyond the side members and inset from the front of the protector and below its top, said projecting portions being adapted to be built into a wall, and said portions having openings forming key ways for mortar.

In testimony whereof I affix my signature.

PAUL COMBS.
